REFRIGERATING APPARATUS

Filed April 29, 1931

UNITED STATES PATENT OFFICE

WARREN H. F. SCHMIEDING, OF DAYTON, OHIO, ASSIGNOR TO FRIGIDAIRE CORPORATION, OF DAYTON, OHIO, A CORPORATION OF DELAWARE

REFRIGERATING APPARATUS

Application filed April 29, 1931. Serial No. 533,758.

The present invention relates to refrigerating apparatus and more particularly to refrigerating apparatus of the compression type wherein a lubricant is circulated in a closed cycle with the refrigerant.

Heretofore in refrigerating systems of the compression type trouble has been experienced because oil employed to lubricate operating parts of the system has accumulated 10 on the walls and on top of the liquid refrigerant within the evaporator. This accumulation of oil on the walls and within the evaporator becomes very viscous, as the temperature of the evaporator is reduced, and 15 forms a thick layer or blanket of the refrigerant which hinders or retards evaporation of the liquid refrigerant contained in the evaporator.

An object of the present invention is to 20 provide an evaporator of a refrigerating system with means which utilizes the difference in pressure created therein for its operation to agitate the liquid refrigerant and destroy the blanketing effect of the layer of lubricant.

Another object of the invention is to provide means within an evaporator which will 25 agitate liquid refrigerant beneath a layer of lubricant floating thereon during each cycle of operation of a refrigerant liquefying unit operatively connected with the evaporator.

Further objects and advantages of the present invention will be apparent from the following description, reference being had to 30 the accompanying drawing, wherein a preferred form of the present invention is clearly shown.

In the drawing:

Fig. 1 is a vertical section through a portion of an evaporator having my invention embodied therein and having a refrigerating system shown diagrammatically adapted to 40 be connected with the evaporator; and

Fig. 2 is an enlarged sectional view of a portion of the evaporator taken on the line 45 2-2 of Fig. 1.

For the purpose of illustrating the present invention I have shown in Fig. 1 a compressor-condenser-expander type of refrigerating system having an evaporator 10

shown in section on a large scale and including connections 11 and 12 for operatively connecting the evaporator with the system. In addition to the evaporator the system includes a compressor 13, a condenser 14 and 55 a reservoir or liquid refrigerant tank 15. Refrigerant vapor is withdrawn from the evaporator 10 through the vapor or low pressure conduit 16 and is liquefied in the condenser 14 and returned to the evaporator through the liquid or high pressure conduit 17. The compressor is operated by a motor 18 controlled by an automatic switch 19 which may be actuated in response to the refrigerating demand, for example by a pressure-responsive device 21 connected to the low pressure conduit 16. It is obvious, in systems of 60 the type disclosed, to state that the pressure-responsive device 21 which actuates the switch 19 for controlling the electric circuit to the motor is adjusted to operate between certain pressure limits. Since pressures and 65 temperatures of the refrigerant increase or decrease uniformly it is apparent that the device 21 is adapted to maintain certain predetermined temperature limits within the evaporator of the system.

At the beginning of operation of the system the period of time between starting of the motor and compressor and stopping thereof 70 is referred to as the "on phase" of a cycle of operation of the refrigerant liquefying unit. The period of time between two successive operating periods or "on phases" of the refrigerant liquefying unit is referred to as 75 an "off phase" of a cycle of operation of the unit. Thus it is apparent that while the system is in operation to produce refrigeration, the refrigerant liquefying unit is cyclically 80 operation and that each cycle thereof includes 85 an "on phase" and an "off phase".

Referring to Fig. 1, evaporator 10 comprises a header 24 forming a reservoir for liquid refrigerant, and a plurality of ducts 25 depending from the header 24 for circulating refrigerant to a point remote from the reservoir such for example to a lower header 25a. The liquid refrigerant indicated at 26 is kept at a constant level 27 by a valve 28 which controls a liquid refrigerant inlet open- 90 95 100

ing 29 extending from the connection 11 through an end plate 30. Valve 28 is actuated in response to the liquid refrigerant level by a float 31. The liquid refrigerant 5 is supplied to the evaporator through the inlet connection 11 and the vapor or gaseous refrigerant is withdrawn through the connection 12 connected to the vapor conduit 16.

The apparatus, or system, as generally described above is lubricated by placing a quantity of oil in the crankcase of the compressor and depending upon the splashing of rotating parts to distribute oil throughout the compressor. Some of the oil is dissolved in 15 the refrigerant and some of the oil is mechanically pumped by the compressor to the condenser and reservoir and eventually to the evaporator. The oil in separating by gravity from the refrigerant in the evaporator forms globules which adhere to the walls thereof and tend to remain stationary. These globules of oil form a layer of insulation between the liquid refrigerant in the evaporator and the walls thereof which insulation retards 20 the conduction of heat from the evaporator wall to refrigerant contained therein and consequently evaporation of the refrigerant is also retarded. Finally after the refrigerant absorbs sufficient heat to cause its evaporation 25 a disturbance occurs in the evaporator and the globules of oil are carried to the top of the liquid refrigerant. The refrigerant continues to boil off in the evaporator, leaving the oil, which collects in a layer of from $\frac{1}{2}$ " to $1\frac{1}{4}$ " thick on top of the refrigerant. This layer of oil on top of the refrigerant in the evaporator becomes more viscous as the temperature of the evaporator is reduced and forms a heavy blanket on top of the refrigerant, the effect of which must be destroyed before evaporated refrigerant can enter the space above the oil so as to affect the pressure responsive device which controls the starting and stopping of the motor and compressor. 35

This collection or accumulation of oil in the evaporator is particularly harmful when the system is used to refrigerate an ice cream cabinet or the like, wherein very low temperatures are desired to be maintained. Under 40 such conditions within the evaporator of the system the compressor will be operated frequently and only for short intervals of time, thus causing short operating cycles of the compressor. These "short cycles" of the compressor are caused by the compressor creating a suction in the low pressure conduit 16 and in the space above the liquid level within the header 24 of the evaporator, sufficient to cause the pressure-responsive device 21 to 45 actuate the automatic switch 19 and break the electric circuit to the motor 18, thus stopping the compressor, without breaking up the layer of oil in the evaporator, thereby preventing liquid refrigerant below the layer of oil from vaporizing. Obviously such short

cycles of the compressor will continue for awhile and the evaporator will not be reduced to the temperature at which the pressure-responsive device 21 has been set to maintain therein. Consequently the motor which 50 drives the compressor is stopped before the refrigerant vaporizes and therefore the desired temperature will not be maintained. During these short cycles, the refrigerant temperature rises and consequently the pressure increases below the oil. When this pressure increases to a point sufficient to break through the oil blanket, a violent ebullition or explosion occurs causing a large quantity 55 of liquid refrigerant to flow into the outlet 80 of the evaporator.

During short operating cycles of the compressor, as hereinbefore described, it is obvious that the layer or blanket of lubricant floating on the liquid refrigerant within the evaporator will cause a pressure differential in the evaporator. This pressure differential is caused by the weight of the lubricant together with its viscosity and its adhesion to walls of the evaporator. This inherent 65 characteristic is commonly referred to as the "static head" of the lubricant. Such pressure differential permits the space in the evaporator above the layer of oil to be reduced, by suction of the compressor, considerably more than the "static pressure" of the liquid refrigerant below the oil. Under normal conditions, with a minimum amount or thickness of a layer of oil in the evaporator, this pressure differential is not as great as 70 under abnormal conditions when a large quantity or thick layer of oil is contained in the evaporator. However, under all conditions, when the compressor operates, there is a sufficient pressure differential to cause the 75 pressure responsive device to actuate and stop operation of the compressor before the pressure is substantially equalized throughout the entire interior of the evaporator. Thus the layer of oil creates a lag of considerable extent in evaporation of the refrigerant 80 unless the refrigerant is agitated during the operating phase of the compressor unit so that the blanketing effect of the oil is destroyed. This lag or retardation of refrigerant evaporating from the body of liquid refrigerant in an evaporator causes the refrigerant which vaporizes to accumulate and remain below the oil until a pressure sufficient 85 to break through the heavy viscous layer of oil is created. Such accumulation of vaporized refrigerant beneath the oil, upon breaking through the oil, causes liquid refrigerant to be splashed into the gaseous refrigerant outlet leading from the evaporator. This 90 thereby causes refrigeration outside the compartment, to be refrigerated by the evaporator, and renders the system inefficient.

My invention is directed to a system in which the difference in pressure created and

occurring in the evaporator, due to the cyclical operations of the compressor, is utilized to actuate a device which agitates liquid refrigerant beneath a layer of oil floating thereon so as to destroy the blanketing effect or "static head" of the oil, and consequently the pressure differential within the evaporator, for causing evaporation of the liquid refrigerant during operation of the compressor. By causing vaporization of refrigerant beneath the oil in an evaporator, during the operating phase of each cycle of the compressor, pressures and consequently temperatures throughout the entire interior of the evaporator will be substantially equalized. Thus, the pressure responsive device which actuates the electric switch to start and stop the motor connected with the compressor will be rendered more efficient for controlling cyclical operation of the system between certain definite pressures and the effect of the oil as hereinbefore pointed out will be destroyed, thereby rendering the evaporator suitable for maintaining a more constant and uniform temperature. Also by agitating liquid refrigerant within an evaporator, during each cycle of the refrigerant liquefying unit, evaporated refrigerant will be prevented from accumulating below the layer of oil and short operating cycles of the compressor and therefore splashing of liquid refrigerant into the outlet of the evaporator will be eliminated.

Referring now to Fig. 1 I have provided means to destroy the blanketing effect of lubricant floating on liquid refrigerant in an evaporator for causing the evaporator to maintain a substantially constant temperature. This means includes a flexible disc or diaphragm 40 sealed in any suitable manner to a circular shaped relatively flat plug 41 which plug is screw-threaded into a wall of the header 24 of the evaporator 10. Diaphragm 40 has a member 42 soldered thereto for receiving one end of a rod 43 which rod extends downwardly therefrom, through the layer of oil in the evaporator, and into the lower portion of the body of liquid refrigerant 26 in one of the ducts 25 of the evaporator 10. The rod 43 has a plurality of discs or fins 44 secured thereto and extending outwardly therefrom but spaced from the inner wall of duct 25. Rod 43 also has one or more discs or fins 45 secured thereto and extending outwardly therefrom for loosely engaging the interior wall of a duct 25. The fins or discs 45 serve as a guide for the rod 43 so that its operation or vertical movement will not be prevented. Flow of refrigerant past the discs 45 is permitted through openings 46 provided therein. Plug 41 which carries the diaphragm 40 includes a closed chamber 48, of any suitable size, which preferably contains air sealed therein at atmospheric pressure. Diaphragm 40 has one of its sides responsive to conditions within the chamber 48

and its other side responsive to conditions or pressure within the evaporator 10. A gasket 49 interposed between the plug 41 and the wall of header 24 prevents leakage of refrigerant at this point. The plug 41 is provided with countersunk openings 51 adapted to receive a suitable wrench for tightening the plug 41 in position and for loosening the plug from the header 24 in order to remove the diaphragm 40 and rod 43 secured thereto from the evaporator 10.

During operation of the system as previously described, the compressor 13 upon being operated withdraws gaseous refrigerant from the evaporator 10 and creates a vacuum or suction pressure in the space above the oil or lubricant floating in the liquid refrigerant therein. The chamber 48 and diaphragm 40 are constructed and adjusted so that the vacuum or suction pressure created by the compressor 13 will reduce the pressure exerted on one side of the diaphragm and cause it to move or to be snapped, into the position shown by the dotted lines in Fig. 1 of the drawing sometime during operation of the compressor, preferably and for the purpose of rendering the device infallible in its operation, just prior to the time suction pressure increases to a point sufficient to effect the pressure responsive device 21 to stop the compressor.

This preference permits a more rugged construction of the chamber 48 and diaphragm 40 so that the diaphragm can be actuated between a wider range of pressure. The snapping or movement of the diaphragm 40 causes rod 43 connected thereto to be moved and also the discs or fins 44 and 45 secured to the rod. It is obvious that this snap action or movement of the discs 44 and 45 will agitate the refrigerant contained in the evaporator 10, causing evaporation thereof and consequently the blanketing effect of the layer of oil above the refrigerant will be destroyed. Furthermore, such disturbances cause pressures both above and below the layer of oil in the evaporator to be substantially equal, thereby insuring that the compressor will not be stopped before the evaporator has been reduced to the desired low pressure and consequently temperature. Vaporized refrigerant below the layer of oil in the evaporator is also prevented from accumulating, therefore violent ebullition of the liquid refrigerant is prevented and uniform evaporation of the refrigerant occurs, thus eliminating splashing of liquid refrigerant into the gaseous refrigerant outlet of the evaporator.

After the pressure within the evaporator, below and above the layer of oil on the liquid refrigerant therein, has been substantially equalized and the compressor creates a sufficient suction pressure to effect the pressure responsive device 21 to stop operation of the

compressor, pressure will then increase within the evaporator, due to evaporation of liquid refrigerant contained therein, and will snap or cause the diaphragm 40 to be moved 5 to the position shown in full lines in the drawing. It is thus apparent that the diaphragm 40 is again in position to cause agitation of the refrigerant in the evaporator upon the next succeeding operating phase 10 of a cycle of the refrigerant liquefying unit.

Although I have described the chamber 48 as containing air sealed therein at atmospheric pressure, it may however be desirable to partially evacuate the chamber 48 of its 15 air content or to charge the chamber with a suitable volatile fluid. For this purpose I have provided a tube 53 secured to the plug 41 which tube serves as a means for evacuating or filling the chamber 48 with a fluid if 20 desired. After partially evacuating or filling the chamber 48, this tube 53 is adapted to be bent and soldered so as to seal the chamber. It is to be further understood that the rod 43 and discs 44 and 45 secured thereto 25 must be constructed of material which is light in weight so as to prevent their weight from impairing operation of the diaphragm 41 utilized to actuate the rod 43. However, it may be desirable to provide some well known 30 means, such as springs or the like for example, for counterbalancing the weight of rod 43 and the discs secured thereto.

From the foregoing it is apparent that I have provided an improved apparatus which 35 is sure in its operation and which functions efficiently when the system is operating to maintain a very low temperature, which low temperature increases the viscosity of lubricant, while at the same time providing means 40 for preventing the lubricant from retarding evaporation of liquid refrigerant in the evaporator by destroying the oil blanket prior to the "cut-out" setting of the switch so that vaporization will take place every time the 45 compressor is started. With the hereinbefore enumerated difficulties eliminated, evaporators employed to produce very low temperatures are rendered more efficient for maintaining a constant range of temperature. Likewise the life of the compressor 50 and its operating motor is prolonged by the prevention of the heretofore described short operating cycles thereof.

While the form of embodiment of the invention as herein disclosed constitutes a preferred form, it is to be understood that other forms might be adopted, all coming within the scope of the claims which follow.

What is claimed is as follows:

30 1. In a refrigerating system of the type in which a body of liquid refrigerant is maintained in an evaporator and in which a layer of lubricant floats on the liquid refrigerant in the evaporator, the combination of an 35 evaporator, means for supplying liquid re-

frigerant to and for withdrawing gaseous refrigerant from said evaporator, means for starting and stopping said first named means, means for agitating the liquid refrigerant in said evaporator to destroy the blanketing effect of the lubricant, said last named means including a portion disposed below the liquid level in said evaporator, and means responsive during each cycle due to the cyclical operations of said first 75 named means for actuating said portion of said last named means.

2. In a refrigerating system of the type in which a body of liquid refrigerant is maintained in an evaporator and in which a layer of lubricant floats on the liquid refrigerant in the evaporator, the combination of an evaporator, means for supplying liquid refrigerant to and for withdrawing gaseous refrigerant from said evaporator, means for starting and stopping said first named means, 80 means for agitating the liquid refrigerant in said evaporator to destroy the blanketing effect of the lubricant, said last named means including a portion disposed below the liquid level in said evaporator, and means responsive during the latter part of the operating phase of each cycle of said first named means for actuating said portion of said last named 85 means.

3. In a refrigerating system of the type in which a body of liquid refrigerant is maintained in an evaporator and in which a layer of lubricant floats on the liquid refrigerant in the evaporator, the combination of an evaporator, means for supplying liquid refrigerant to and for withdrawing gaseous refrigerant from said evaporator, means for starting and stopping said first named means, means for agitating the liquid refrigerant in said evaporator to destroy the blanketing effect of the lubricant, said last named means including a portion disposed below the liquid level in said evaporator, and means responsive during the operating phase of each cycle of said first named means for actuating said portion of said last named 90 means.

4. In a refrigerating system of the type in which a body of liquid refrigerant is maintained in an evaporator and in which a layer of lubricant floats on the liquid refrigerant in the evaporator, the combination of an evaporator, means for preventing liquid refrigerant from rising above a predetermined level in said evaporator, means in addition to said first named means for agitating the liquid refrigerant in said evaporator to destroy the blanketing effect of the lubricant, said second named means including a portion disposed below the liquid level in said evaporator, and means responsive to conditions within said evaporator for actuating said portion of said agitating means.

5. In a refrigerating system of the type in which a body of liquid refrigerant is main- 113

- tained in an evaporator and in which a layer of lubricant floats on the liquid refrigerant in the evaporator, the combination of an evaporator, means for preventing liquid refrigerant from rising above a predetermined level in said evaporator, means in addition to said first named means for agitating the liquid refrigerant in said evaporator to destroy the blanketing effect of the lubricant, said second named means including a portion disposed below the liquid level in said evaporator, and means responsive to pressures within said evaporator for actuating said portion of said agitating means. 5
6. In a refrigerating system of the type in which a body of liquid refrigerant is maintained in an evaporator and in which a layer of lubricant floats on the liquid refrigerant in the evaporator, the combination of an evaporator, means for preventing liquid refrigerant from rising above a predetermined level in said evaporator, means in addition to said first named means for agitating the liquid refrigerant in said evaporator to destroy the blanketing effect of the lubricant, said second named means including a portion disposed below the liquid level in said evaporator, and means for actuating said portion of said agitating means. 10
7. In a refrigerating system of the type in which a body of liquid refrigerant is maintained in an evaporator and in which a layer of lubricant floats on the liquid refrigerant in the evaporator, the combination of an evaporator, means for preventing liquid refrigerant from rising above a predetermined level in said evaporator, means in addition to said first named means for agitating the liquid refrigerant in said evaporator to destroy the blanketing effect of the lubricant, said second named means including a portion disposed below the liquid level in said evaporator, and means for actuating said portion of said agitating means. 15
8. In a refrigerating system of the type in which a body of liquid refrigerant is maintained in an evaporator and in which a layer of lubricant floats on the liquid refrigerant in the evaporator, the combination of an evaporator, means for preventing liquid refrigerant from rising above a predetermined level in said evaporator, means in addition to said first named means for agitating the liquid refrigerant in said evaporator to destroy the blanketing effect of the lubricant, said second named means including a portion disposed below the liquid level in said evaporator, and a movable member connected with said portion of said agitating means for actuating the same, said member being moved in response to conditions within said evaporator. 20
9. In a refrigerating system of the type in which a body of liquid refrigerant is maintained in an evaporator and in which a layer of lubricant floats on the liquid refrigerant in the evaporator, the combination of an evaporator, means for preventing liquid refrigerant from rising above a predetermined level in said evaporator, means in addition to said first named means for agitating the liquid refrigerant in said evaporator to destroy the blanketing effect of the lubricant, said second named means including a portion disposed below the liquid level in said evaporator, and a snap acting diaphragm connected with said portion of said agitating means for actuating the same, said diaphragm being moved in response to pressures within said evaporator. 25
10. In a refrigerating system of the type in which a body of liquid refrigerant is maintained in an evaporator and in which a layer of lubricant floats on the liquid refrigerant in the evaporator, the combination of an evaporator, means for supplying liquid refrigerant to and for withdrawing gaseous refrigerant from said evaporator, means for starting and stopping said first named means, means for destroying the blanketing effect of the lubricant floating on the liquid refrigerant in said evaporator, said last named means including a vertical member extending through the layer of oil and into the liquid refrigerant, and means connected with said member and responsive during each cycle due to the cyclical operations of said first named means for actuating said member to agitate the liquid refrigerant in said evaporator. 30
11. In a refrigerating system of the type in which a body of liquid refrigerant is maintained in an evaporator and in which a layer of lubricant floats on the liquid refrigerant in the evaporator, the combination of an evaporator, means for supplying liquid refrigerant to and for withdrawing gaseous refrigerant from said evaporator, means for starting and stopping said first named means, means for destroying the blanketing effect of the lubricant floating on the liquid refrigerant in said evaporator, said last named means including a vertical member extending through the layer of oil and into the liquid refrigerant, and means connected with said member and responsive during each cycle due to the cyclical operations of said first named means for actuating said member, said member having a plurality of discs secured thereto for agitating liquid refrigerant in said evaporator upon movement of the member. 35
12. In a refrigerating system of the type in which a body of liquid refrigerant is maintained in an evaporator and in which a layer of lubricant floats on the liquid refrigerant in the evaporator, the combination of an evaporator, means for supplying liquid refrigerant to and for withdrawing gaseous refrigerant from said evaporator, means for starting and stopping said first named means, means for destroying the blanketing effect of the lubricant floating on the liquid refrigerant in said evaporator, said last named means including a vertical member extending through the layer of oil and into the liquid refrigerant, and means connected with said member and responsive during each cycle due to the cyclical operations of said first named means for actuating said member, said member having a plurality of discs secured thereto for agitating liquid refrigerant in said evaporator upon movement of the member. 40

- liquid refrigerant to and for withdrawing gaseous refrigerant from said evaporator, means for starting and stopping said first named means, means for destroying the blanketing effect of the lubricant floating on the liquid refrigerant in said evaporator, said last named means including a vertical member extending through the layer of oil and into the liquid refrigerant, and means connected with said member and responsive during the latter part of the operating phase of each cycle of said first named means for actuating said member to agitate the liquid refrigerant in said evaporator.
13. In a refrigerating system of the type in which a body of liquid refrigerant is maintained in an evaporator and in which a layer of lubricant floats on the liquid refrigerant in the evaporator, the combination of an evaporator, means for supplying liquid refrigerant to and for withdrawing gaseous refrigerant from said evaporator, means for starting and stopping said first named means, means for destroying the blanketing effect of the lubricant floating on the liquid refrigerant in said evaporator, said last named means including a vertical member extending through the layer of oil and into the liquid refrigerant, and means connected with said member and responsive during the operating phase of each cycle of said first named means for actuating said member to agitate the liquid refrigerant in said evaporator.
14. In a refrigerating system of the type in which a body of liquid refrigerant is maintained in an evaporator and in which a layer of lubricant floats on the liquid refrigerant in the evaporator, the combination of an evaporator, means for supplying liquid refrigerant to and for withdrawing gaseous refrigerant from said evaporator, means for starting and stopping said first named means, means for destroying the blanketing effect of the lubricant in said evaporator, said last named means including a vertical member extending through the layer of oil and into the liquid refrigerant, and means connected with said member and responsive during the operating phase of each cycle of said first named means for actuating said member, said member having a plurality of discs secured thereto and extending outwardly therefrom for agitating liquid refrigerant in said evaporator upon movement of the member.

In testimony whereof I hereto affix my signature.

WARREN H. F. SCHMIEDING.
